UNITED STATES PATENT OFFICE.

ALBERT BABENDREIER, OF BALTIMORE, MARYLAND, ASSIGNOR OF ONE-HALF TO FRED L. BABENDREIER, OF WASHINGTON, D. C.

TRITURATOR.

SPECIFICATION forming part of Letters Patent No. 336,618, dated February 23, 1886.

Application filed May 20, 1885. Serial No. 166,404. (No model.)

To all whom it may concern:

Be it known that I, ALBERT BABENDREIER, a citizen of the United States, residing at Baltimore, in the State of Maryland, have invented 5 certain new and useful Improvements in Triturators; and I do declare the following to be a full, clear, and exact description of the invention, such as will enable others skilled in the art to which it appertains to make and use the 10 same, reference being had to the accompanying drawings, and to the letters and figures of reference marked thereon, which form a part of this specification.

Figure 1 is a perspective view of my improved triturator with the doors swung open and a part of the casing removed, so as to expose the operating parts. Fig. 2 is a longitudinal vertical sectional view taken centrally through the machine. Fig. 3 is a vertical 20 transverse sectional view taken on the line $x-x$ in Fig. 2. Fig. 4 is a vertical transverse sectional view taken on the line $y-y$ in Fig. 2. Fig. 5 is a horizontal sectional view taken on the line $z-z$ in Fig. 2. Fig. 6 is a side view 25 showing the pestle-carrying frame raised for the purpose of affording access to the mortar. Fig. 7 is a horizontal sectional view taken on the line $v-v$ in Fig. 2. Fig. 8 is a detail view of the scraping attachment for the mortar; 30 and Fig. 9 is a perspective detail view of one of the clamps for holding the mortar.

The same letters refer to the same parts in all the figures.

This invention relates to triturating-machines, and it has for its object to provide a 35 device of this class which shall possess superior advantages in point of simplicity, durability, and general efficiency.

With these ends in view it consists in the 40 improved construction, arrangement, and combination of parts, which will be hereinafter fully described, and particularly pointed out in the claims.

In the drawings hereto annexed, A designates a suitable frame or casing, the lower 45 portion of which is to be provided with swinging doors B B for the purpose of protecting the operating parts inclosed therein. The rear end of the frame or casing is provided 50 with an upright or bracket, C, which, together

with the base, affords bearings for the vertical main shaft D, to which a rotary motion may be imparted by hand or from any suitable motive power. Arranged within the frame or casing, in front of the said main shaft, are 55 a pair of vertical rods or standards, E E, forming supports for a vertically-adjustable box, F, having laterally-extending ears or lugs, G G, which are perforated for the reception of the rods E E, and provided with set-screws 60 H, whereby they may be held upon the said rods in any position to which they may be adjusted. The box F is provided with interior grooves or guides I, forming bearings for a longitudinally-reciprocating slide, J, the 65 rear end of which is provided with a pin, K, adapted to work in a cam-groove, L, in a disk, M, which is vertically adjustable upon the main shaft by means of a set-screw, N, passing through the hub or collar of the said disk. 70 It will thus be seen that when the main shaft revolves a longitudinal reciprocating motion is imparted to the slide J.

Arranged in front of the rods or standards E E are a pair of brackets, O O, between which 75 a lever, P, is pivoted adjustably upon a pin, Q, which may be adjusted in any one of a series of perforations, R R, in the said brackets and lever, the stroke of which latter may thereby be regulated. The said lever is operated by means of the slide J, the front end of which is provided with a pin, S, passing transversely through a vertical slot, T, in the lever. The stroke of the lever may also be regulated 80 by raising or lowering the box forming the bearing for the slide J, as occasion may demand.

U is a longitudinal shaft journaled horizontally in the frame or casing in suitable hangers, V V, said shaft passing through a vertical 85 slot or opening, W, in the lever P.

X is a suitably-constructed frame mounted to slide upon the front end of the shaft U, and having a transverse pin, Y, on which is pivoted a pitman or rod, Z, connecting the said frame with the upper end of the lever P, which is provided with a slot, A', for the reception of the connecting-pin. The pitman Z is composed of a socket, B', and a sliding extension-rod, C', connected by a set-screw, D', in order 90 to

that the distance between the lever P and sliding frame X may be regulated. The upper part of the frame X extends through a slot, E', in the top of the frame or casing A, and is 5 provided with a plate or support, F', arranged to slide upon a track formed by a pair of metallic strips, G', thereby taking the weight off the shaft U. The frame X has bearings for a vertical shaft, H', extending through the plate 10 F', and provided at its lower end with a pinion, I', meshing with a pinion, J', which slides upon the shaft U, but is connected with the latter, so as to revolve therewith, by means of a pin, K', passing through the hub or collar 15 of the said pinion and entering a longitudinal groove in the said shaft. The pinion J' is connected with the frame X, and made to slide therewith, and held in mesh with the pinion I' by means of a pair of suitably-arranged 20 bracket-strips, L' L'. The rear end of the shaft U has a longitudinally-sliding pinion, M', arranged to be operated by means of a clutch-lever, N', whereby it may be thrown into or out of mesh with a pinion, O', upon 25 the main shaft D, from whence a rotary motion may thus at will be imparted to the said shaft U. The upper end of the shaft H' carries a disk, P', having a series of three or more radial dovetailed slots, Q', adapted to receive 30 the clamping or holding devices for the mortar R', which is mounted or supported upon the said plate. The said clamping devices consist of plates or blocks S', dovetailed to fit and slide in the slots Q', and provided with 35 flanges T', adapted to rest on the upper surface of the disk, as shown. Said plates or blocks are provided near their inner ends with lugs U', in which are pivoted levers V', the inner ends of which have rubber cushions 40 adapted to bite against and hold the flange W' at the bottom edge of the mortar. The outer ends of the blocks S' are provided with wedge-shaped cam-plates X', having upwardly-extending studs Y', on which are pivoted 45 the cam-levers Z', which bear with their wedge-shaped inner ends or heads against the under sides of the levers V', the outer ends of which have perforations fitting over the said studs.

50 It will be seen that by adjusting the sliding blocks until the inner ends of the levers V' bear against the flange at the lower edge of the mortar, and then tightening the cam or clamping levers, the latter will at the same time 55 tighten the sliding blocks upon the disk and the levers V' against the mortar-flange, thereby retaining the mortar securely in position.

This adjusting device is simple and convenient, and it enables the mortar to be attached 60 or removed in a moment's time. It also enables mortars of various sizes to be used with equal facility.

The plate F' of the frame X is provided with an upright, A², having an extension-rod, B², 65 adjustable by a set-screw, C², and provided at its upper end with a socket, D², in which is mounted a sliding arm, E², retained in posi-

tion in the said socket by means of a set-screw, and provided at its outer end with a pivoted rod, F², having a socket, G², at its lower end 70 for the reception of a scraper, H², which may be held in the said socket by means of a set-screw, and which is curved and adapted to fit against the inner surface of the mortar. Between the upper end of the pivoted rod F² and 75 a stud, I², extending upwardly from the adjustable arm E², is interposed a spring, J², by the action of which it will be seen that the said scraper is at all times held in contact with the inner surface of the mortar, against which it exerts a 80 yielding pressure which is efficient in throwing the material which is being triturated toward the center of the mortar, where it may be acted upon by the pestles, and by which construction all danger of breakage is avoided. 85 It will also be seen that by the construction described scrapers of various shapes, and adapted to various mortars, may be readily placed in the holding-socket, which latter may be adjusted vertically and laterally, so as to 90 adapt it to mortars of various dimensions.

It will be seen that by the construction and arrangement of parts thus far described a longitudinal reciprocating motion will be imparted to the frame X carrying the mortar, to 95 which latter a revolving motion is at the same time imparted.

I shall now proceed to describe the second part of the invention, which relates to the pestles, which shall be held against the bottom 10 of the mortar with a yielding pressure, and at the same time be revolved in a direction opposite to that in which the mortar revolves. On the upper side of the frame or casing A is constructed a box or casing, consisting of a 105 permanent or stationary back, K², hinged sides L² L², and a front piece or door, M², which is hinged to the free edge of one of the sides, which may thus be conveniently thrown open so as to afford free access to the mortar, which 110 is inclosed by the said casing. The latter is provided with a suitable top, N². This casing has a rubber lining for the double purpose of making it thoroughly tight and in order to enable it to be easily washed 115 or otherwise cleaned, an object of considerable importance when different materials are to be triturated. The rear side of the back of the said casing is provided with a bracket, O², in which are hinged a pair of forwardly-extending arms, P², between the front ends 120 of which is secured a box or casing, Q², made of metal, and containing the spindles of the pestles and their operating mechanism. In the drawings hereto annexed four spindles, 125 R², have been shown, one of which is arranged centrally between the remaining three, and all arranged in bearings in the upper and lower sides of the casing Q², and in such a manner as to be capable of sliding vertically in their bearings. The said spindles are provided with collars S², arranged to rest upon the bottom of the box or casing, and between these collars 130 and the top of the casing are arranged springs

T^2 , coiled upon the spindles, which are thereby automatically forced in a downward direction. The spindles are provided below the bottom of the casing with adjustable collars U^2 , to limit their movement in an upward direction against the tension of the springs, and to the lower ends of the spindles the pestles V^2 are attached by means of sockets W^2 and set-screws X^2 . The casing Q^2 is provided with upwardly-extending brackets Y^2 , supporting a top plate, Z^2 , having perforations for the passage of the spindles, and between which and the top of the casing are placed the pinions A^3 , one of which is loose upon the central spindle, while the remaining ones are connected with their respective spindles by means of pins B^3 , entering vertical grooves C^3 in said spindles, which are thus capable of moving vertically while they are being operated by the revolution of the said pinions. The outer pinions mesh with and are operated by the central pinion, which is connected securely to the under side of a bevel-gear, D^3 , which is journaled in the top-plate Z^2 . The central spindle extends through the bevel-pinion D^3 , which is loose thereon, and its upper end carries a bevel-pinion, E^3 , which is connected with the said spindle by means of a pin, F^3 , entering the groove therein. The bevel-pinions D^3 and E^3 mesh with opposite sides of a miter-gear, G^3 , mounted upon the front end of a shaft, H^3 , which is journaled in suitable brackets, I^3 , attached to the box or casing Q^2 . It will be seen that when the said shaft is rotated, the center spindle is actuated or caused to revolve by the bevel-gear E^3 , while the bevel-gear D^3 , by means of the pinion attached thereto, will serve to actuate or revolve the remaining spindles, thus causing all of the spindles to revolve in one direction, which shall be opposite to the direction in which the mortar is rotated. The lower ends of the adjustable collars U^2 of the several pestle carrying spindles are provided with cups J^3 , which will serve to prevent any lubricant that may be applied to the said spindles from reaching the lower ends of the same, and getting from thence into the mortar. Suitably attached to the arms P^2 is a box or casing, K^3 , serving to inclose the casing Q^2 , which carries the spindles, as already described. The front of the said casing is provided with a sliding door, L^3 , and to its lower edge is attached the top N^2 of the mortar-inclosing casing. It has been already stated that the arms P^2 are hinged to the bracket O^2 , and it follows that when they are swung or tilted in an upward direction they carry with them the casing Q^2 , with all its attachments, thus leaving the mortar free of access when the doors of its inclosing-casing are swung open, as shown in Fig. 6 of the drawings. The mortar may then be easily removed and another one substituted without danger of interfering with the pestles or of spilling any portion of its contents. The shaft H^3 , which, as before stated, serves to operate the pestle-carrying spindles by

means of the miter-gear G^3 at the front end of said shaft, extends in a rearward direction, as shown, and is provided at its rear end with a miter-gear, M^3 , meshing with the under side of a miter-gear, N^3 , which is secured upon the main shaft D near the upper end of the latter. A pair of uprights or brackets, O^3 O^3 , near the rear end of the frame A are connected by a cross-piece, P^3 , the under side of which has a notch, Q^3 , forming one half of a box or bearing for the rear end of the said shaft H^3 . The other half of said box or bearing is formed by a lever or latch, R^3 , pivoted to one of the uprights O^3 , and adapted to engage and be held in a raised position by means of a catch, S^3 , upon the other of said uprights. By this construction and arrangement of parts the shaft H^3 will, when raised to an operative position, be held securely in its bearings, while on the other hand, by simply lowering the latch-lever R^3 , the rear end of the said shaft will be lowered, enabling the pestle-carrying frame to be raised or tilted, as shown in Fig. 6. It is obvious that the said latch-lever R^3 also serves to hold the miter-gears M^3 and N^3 in mesh with each other for operation.

I shall now proceed to describe a mechanism whereby the mechanism for longitudinally reciprocating the mortar may be thrown out of gear, when desired, without affecting the operation of the pestles or the rotary motion of the mortar. This longitudinally-reciprocating motion, it will be remembered, is effected by means of the lever P , which is pivoted between the brackets O O , and which is operated by means of the slide J , actuated by the cam-grooved disk M . Said lever has been described as being connected with the sliding frame X , carrying the mortar by means of a rod or pitman, Z . I will now explain that the said pitman is bifurcated at its rear end, as shown at T^3 , for the reception of the upper end of the lever P , which has the slot A' for the reception of the connecting-pin U^3 , which passes through the said slot and through the bifurcated rear end of the pitman. The lever P is extended through a suitable slot in the top of the main frame or casing A , and is provided with a pivoted arm or handle, V^3 , to the lower end of which the connecting-pin U^3 is attached. It will be seen that by simply manipulating the handle the said connecting-pin may at any time be readily withdrawn, thus leaving the lever P to continue its motion, while the frame X , with the pitman or connecting rod, remains stationary. The first forward stroke of the lever, however, acting against the rear end of the pitman, carries the latter with its attached sliding frame X in a forward direction to the extreme limit of the stroke, where they remain stationary. This is desirable, because, at the forward end the mortar is most readily accessible, either for removal or inspection, and the pestle-carrying frame may at this point be most readily lifted out of the same. The connecting-pin may be easily reinserted, when desired, by manipulat-

ing the lever or handle V³. It will be seen that the removal of the connecting-pin U³ does not affect the rotary motion of the mortar, which does not cease until the pinions M' and

5 and O' are thrown out of mesh by means of the clutch-lever N', or the machinery is stopped.

From the foregoing description, taken in connection with the drawings hereto annexed, the operation and advantages of this invention will be readily understood by those skilled in the art to which it appertains.

My invention provides, first of all, for a combined rotary and reciprocating motion of the mortar, whereby every particle of its

15 contents is certain to be speedily and effectually subjected to the action of the pestles—far more so, than in cases where a pestle or even a gang of pestles have a reciprocating motion in a given track. To this is added the fact

20 that the entire number of pestles revolve in a direction opposite to that in which the mortar revolves, each individual pestle having a vertically yielding and spring-actuated motion with relation to the mortar. By this arrangement and combination of parts materials may

25 be triturated more rapidly and thoroughly than by any mechanical means with which I am familiar.

The general construction of the machine is 30 simple and inexpensive, and the arrangement of parts is such that access may be readily had to the mortar, or to any part of the operating mechanism.

Of special importance is the facility with 35 which the pestle-carrying frame may be lifted or tilted out of the mortar, and the ease with which the longitudinally-reciprocating motion of the latter may be stopped whenever required.

40 As a whole the machine is simple and useful for the purpose intended.

It is obvious that a single main shaft may be utilized for driving or operating a series or gang of my improved triturators, of which, 45 for instance, four may be arranged cruciform or radiating from a single central vertical operating shaft. The operating mechanism is thereby simplified, and the several machines comprising the set or gang rendered readily 50 accessible to the attendant.

Having thus described my invention, I claim and desire to secure by Letters Patent of the United States—

1. In a triturator, the combination, with 55 pestles and means for revolving the same, of a mortar, mortar-support, and means for revolving and longitudinally reciprocating said mortar-support, as and for the purpose shown and set forth.

60 2. In a triturator, the combination, with the pestles and means for revolving the same, of a mortar, mortar-support, and means for longitudinally reciprocating said mortar and mortar-support, and means for revolving them 65 in a direction opposite to the direction of the revolution of the pestles, as and for the purpose shown and set forth.

3. In a triturator, the combination of a horizontal revolving shaft, a frame mounted upon the same, means for imparting to said frame a longitudinally-reciprocating motion with relation to the shaft, a shaft journaled vertically in said frame and provided at its upper end with a mortar-supporting disk and at its lower end with a pinion, a bevel-gear meshing with the said pinion mounted upon the horizontal shaft and connected with the sliding frame so as to reciprocate with the latter, a mortar supported upon the disk of the vertical shaft, and pestles projecting into the mortar, as and for the purpose shown and set forth.

4. In a triturator, the combination of a horizontal shaft provided with a pinion rotating therewith and free to slide thereon, a frame sliding upon the shaft, a vertical shaft journaled in the frame and having a pinion at its lower end meshing with the pinion upon the horizontal shaft, a vertically-adjustable lever, mechanism for rocking the latter, a pitman connecting the upper end of the lever with the sliding frame, a mortar secured upon the vertical shaft at its upper end, and pestles projecting into the mortar, as and for the purpose shown and set forth.

5. In a triturator, the combination of a mortar, pestles projecting into the mortar, a sliding frame provided with a support for the mortar, means for revolving said support, a vertical oscillating lever, operating mechanism for the latter, and an extensible rod or pitman connecting the said lever with the sliding frame, as and for the purpose shown and set forth.

6. In a triturator, the combination of the mortar, pestles projecting into the mortar, the sliding frame carrying the mortar-supporting disk, means for revolving said disk, the oscillating operating-lever having at its upper end a pivoted arm or lever-handle, the latter carrying at its lower end a pin entering through a slot in the upper end of the operating-lever, and a rod or pitman connecting the operating-lever and the sliding frame and bifurcated and transversely perforated at its rear end for the reception of the connecting-pin, as and for the purpose shown and set forth.

7. In a triturator, the combination of the vertical main shaft, a cam-grooved disk adjustable upon the same, a pair of standards or uprights, a box vertically adjustable upon the same, a slide arranged to reciprocate in the said box and having a pin engaging the cam-grooved disk, a pair of brackets, an oscillating lever vertically adjustable between the same and having a slot connected with the front end of the reciprocating slide, a longitudinally-reciprocating frame having a revolving vertical shaft, a mortar secured upon the said shaft, pestles entering said mortar, and a rod or pitman connecting the lever with the reciprocating frame, as and for the purpose shown and set forth.

8. In a triturator, the combination of a cas-

ing or frame, a horizontal revolving shaft mounted in the same, a mortar, pestles projecting into the said mortar, a sliding frame having a vertical shaft supporting the mortar, intermediate gearing whereby it is operated by the horizontal shaft, a plate at the upper end of the reciprocating frame extending through a slot in the top of the outer casing, and supporting slides or tracks for the said plate secured upon the top of the frame, as and for the purpose shown and set forth.

9. The combination, with a mortar and pestles, of a mortar-supporting disk having radial dovetailed slots and clamping devices consisting of dovetailed blocks having laterally-extending flanges, pivoted clamping-levers, wedge-shaped cam-plates having studs at the rear ends of the said blocks, and cam-levers pivoted on the said studs with their 15 wedge-shaped heads and bearing against the under sides of the rear ends of the clamping-levers, as and for the purpose shown and set forth.

10. The combination, with a mortar and pestles, of a mortar-supporting disk having radial dovetailed recesses, dovetailed blocks sliding in the said recesses, clamping-levers pivoted upon the upper faces of the said blocks, and cam devices bearing between the outer 20 ends of the blocks and of the clamping-levers, as and for the purpose shown and set forth.

11. A mortar-scraping device for triturators, consisting of a foot or upright, a vertically-extensible rod, a laterally-extensible arm 35 at the upper end of the latter having an upwardly-extending stud, a pivoted rod at the outer end of the said arm having a scraper-socket at its lower end, a scraper, and a spring interposed between the upper end of the said 40 rod and the stud extending upward from the laterally-extensible arm, as and for the purpose shown and set forth.

12. In a triturator, the combination, with the pestles and mortar and a revolving support for the said mortar, of an upright having a vertically-extensible rod provided with a laterally-extensible arm, a pivoted scraper-socket at the outer end of the latter, a scraper in the socket, and a spring forcing the scraper 50 and socket against the side of the mortar, as and for the purpose shown and set forth.

13. In a triturator, the combination of a mortar and pestles and an inclosing casing having hinged sides and a door hinged to one 55 of the said sides, all being lined with sheet-rubber, as and for the purpose shown and set forth.

14. In a triturator, the combination, with a mortar, a sliding frame having a mortar-support, means for reciprocating the frame, and means for revolving the mortar-support, of a gang of pestles and means for revolving each upon its own axis in a direction opposite

to that in which the mortar revolves, as and for the purpose shown and set forth.

15. In a triturator, the combination, with a mortar and means for revolving the same, of a gang of pestles and means for revolving each upon its own axis, as and for the purpose shown and set forth.

16. In a triturator, the combination, with a mortar and means for reciprocating and revolving the same, of a gang of vertically sliding pestles having pinions at their upper ends, springs for forcing each of the pestles downward, a pinion centered between the pinions of the pestles and meshing with the same, and means for revolving the said pinion in the same direction as the mortar, as and for the purpose shown and set forth.

17. In a triturator, the combination of a mortar, a hinged or tilting pestle-carrying frame above the mortar, pestles journaled in the said frame, the pestle-operating shaft extending rearwardly from the said frame and having a miter-gear at its rear end, a vertical operating-shaft provided with a corresponding miter-wheel, a fixed upper half-box for the rear end of the pestle-operating shaft, a pivoted arm or lever forming a lower half-box 85 for the same, and a latch or catch to retain the arm with the box in its raised or operative position, as and for the purpose shown and set forth.

18. In a triturator, the combination of a 95 mortar, a pestle-carrying frame above the mortar, a series of pestles having spindles mounted and arranged to slide vertically in the same and provided with collars, coiled springs within the frame upon the pestle-spindles 100 bearing against the collars and forcing them in a downward direction, gear-wheels sliding upon said spindles and having pins engaging vertical grooves in the latter, and mechanism for actuating the said gears so as to rotate all 105 of the spindles simultaneously in one direction, as and for the purpose shown and set forth.

19. In a triturator, the combination of a 110 mortar, a pestle-carrying frame above the mortar, pestles having their spindles mounted and arranged to slide vertically in the same, springs arranged to force the pestles downward, collars secured adjustably upon the pestle spindles below the casing to limit the upward motion of the pestles, and cups at the lower ends of the said collars for catching lubricating material, as and for the purpose shown and set forth.

In testimony whereof I affix my signature 120 in presence of two witnesses.

ALBERT BABENDREIER.
